(57) **CLAIM**

The ornamental design for a collapsible stand, as shown and described.

DESCRIPTION

FIG. 1 is a perspective view of a front side of a preferred embodiment of the collapsible stand of the invention showing a tank supported thereby;

FIG. 2 is a perspective view of the front side thereof;

FIG. 3 is an elevation view of a first side thereof;

FIG. 4 is an elevation view of the front side thereof;

FIG. 5 is an elevation view of a second side thereof;

FIG. 6 is an elevation view of a rear side thereof;

FIG. 7 is a top view thereof; and,

FIG. 8 is a bottom view thereof.

The broken lines showing the tank and a lock in FIG. 1 are for illustrative purposes only and form no part of the claimed design.

The legs in FIGS. 2-8 are shown fragmented to indicate indeterminate length.
